UNITED STATES PATENT OFFICE

EDWARD L. C. CLARK, OF TAUNTON, MASSACHUSETTS, ASSIGNOR TO MIEHLE PRINTING PRESS & MANUFACTURING COMPANY, OF CHICAGO, ILLINOIS, A CORPORATION OF ILLINOIS.
INK-FOUNTAIN FOR PRINTING-PRESSES.

1,231,567.

Specification of Letters Patent.

Patented July 3, 1917.

Application filed September 16, 1914. Serial No. 861,938.

To all whom it may concern:

Be it known that I, EDWARD L. C. CLARK, a citizen of the United States, residing at Taunton, in the county of Bristol and State 5 of Massachusetts, have invented certain new and useful Improvements in Ink-Fountains for Printing-PresSES, of which the following is a specification.

The invention has for its principal objects the provision of an ink fountain mechanism providing for swinging the ink blade between a position in operative relation to the roll, and a position removed from the roll, and readily accessible for cleaning, and 15 the like, and combined therewith means for variably adjusting the ink blade throughout its length, and so arranged as not to be disturbed in the swinging of the blade out of and again into operative position relative 20 to the ink roll; also other novel and advantageous characteristic features which will hereinafter be made apparent.

In order that the constructional features of the invention and their mode of operation may be readily understood by those skilled in this art a preferred embodiment of the same is set forth in the accompanying drawings and in the subjoined description, based, thereon. As the invention is 25 capable of embodiment in other and varied constructional forms it is to be understood that the drawing and description are to be taken in an illustrative and not in an unnecessarily limiting sense. In the drawing,

Figure 1 is an end elevation of a printing press having the invention embodied therein;

Fig. 2 is an enlarged fragmentary view of 40 certain parts in the position shown in Fig. 1;

Fig. 3 is a vertical section taken on the line 3—3 of Fig. 2;

Fig. 4 is an irregular vertical section through the ink roll and fountain, showing 45 the latch mechanism in end elevation; and

Fig. 5 is a vertical section on the line 5—5 of Fig. 2.

As illustrated the ink fountain is associated in an ordinary printing press with 50 the ink distributing train of rolls and form cylinder the arrangement of which forms no part of the present invention and requires no further description. The ink roll indicated at 11 as carried by the shaft 12, 55 rotates between bracket members 13 within

which is inclosed the ink trough which includes a bottom member 14 hinged at 15 to the brackets 13; forming end members of the trough, at a point eccentric to the journals of the shaft 12. From the sides 16 60 of the bottom member 14 project studs 17 which operate within a guide slot 18 formed in a latch member 19 hinged at 20 to the brackets 13. The slot 18 has an angular offset portion 21 within which the stud 17 is 65 adapted to engage when the trough bottom member is swung to its upper position as represented in Fig. 3. Upon the upper face of the bottom member 14 is mounted an ink plate 22 of thin sheet metal having a certain flexibility and that edge of the ink plate nearest the hinge 15 is arranged to occupy a position closely adjacent the periphery of the ink roll when the trough bottom is 700 swung to its upward position (Fig. 3). 750

In order that the amount of ink transferred to the ink roll 11 may be varied locally throughout its length as the nature of the work requires, it is necessary that the relation between the periphery of the ink 800 roll and the edge of the ink plate shall be absolutely controllable throughout the length of the plate, and to provide for this independent adjustment set screws 23 are mounted at frequent intervals longitudinally of the member 14 being arranged obliquely with reference to the plate with their coned forward ends 24 bearing upon the margin of the ink plate 22 from the under side thereof closely adjacent the edge. 850 These set screws being independently adjustable within the trough bottom 14 it is made possible to closely regulate the relation between the roll and plate throughout the length thereof. 900

By hinging the bottom of the trough at 15 and thus enabling the trough bottom with the ink plate 22 and the set screws 23 to be swung as an entirety clear of the ink roll and to a horizontal position clear of the 100 ends 13 of the fountain the ink plate is wholly exposed and may be cleaned without disturbing the adjustment of the plate so that when again swung to its upper operative position with the stud 17 in engagement within the angular portions of the slot 21 the ink plate reassumes its adjusted relation to the ink roll without the necessity of readjustment. 105

Upon the shaft 12 of the ink roll is fixed 110

a ratchet wheel 25 engaged by the pawl 26 carried by a pinion 27 which is loosely mounted for oscillatory movement upon the said shaft 12. The pinion 27 is in mesh 5 with a rack 28 arranged to be reciprocated through the link 29 from any convenient moving part of the press. It will be observed that as the reciprocatory rack 28 moves backward and forward the pinion 10 27 is oscillated and by means of the pawl 26 advances the ratchet 25 step by step thus also rotating the ink roll step by step to transfer the ink from the fountain to the ink distributing train.

15 In order to provide for the manual rotation of the ink roller during the preliminary inking up, a hand crank 30 is provided which has a nave formed as a housing 31 surrounding a star cam wheel 32 fixed upon 20 the shaft 12, and within the housing in operative relation to the inner wall thereof and to the cam faces of the star wheel are disposed a plurality of rolling members such as rolls 33. It will be clear that when the 25 crank is rotated in a clockwise direction the housing 31 will be clutched to the cam wheel 32 and thereby the ink roll carried by the shaft 12 will be rotated, and that when the ink roll is rotated by means of the step by 30 step driving mechanism previously described the clutch connection between the housing and cam wheel will be released and the crank 30 will remain inactive, hanging idle.

35 I claim:

1. In an ink fountain, the combination of 40 an ink roll, and an ink trough, the bottom of the trough comprising a plate mounted to move independently of the trough ends to and from a position with its edge adjacent the roll, and a series of adjusting members arranged to bear at intervals on the margin of the plate whereby to regulate the relation of the plate edge and the ink roll, substantially as described.

2. In an ink fountain, the combination of 50 an ink roll, and an ink trough, the bottom of the trough comprising a flexible plate mounted to swing independently of the trough ends to and from a position with its edge adjacent the roll, and a series of adjusting members swinging with the plate and arranged to bear at intervals on the margin of the same whereby to regulate the relation of the plate edge and the ink roll, substantially as described.

3. In an ink fountain, the combination of 60 an ink roll, and an ink trough, the bottom of the trough comprising a flexible plate mounted to swing independently of the trough ends on a pivot eccentric to the ink roll to and from a position with its edge adjacent the roll, and a series of adjusting members arranged to bear at intervals on the margin of the plate whereby to regulate

the relation of the plate edge and the ink roll, substantially as described.

4. In an ink fountain, the combination of 70 an ink roll and an ink trough, the bottom of the trough comprising a plate mounted to swing independently of the trough ends upon a pivot eccentric to the ink roll to and from a position with its edge adjacent the roll, and a series of set screws swinging with the plate and arranged to bear at intervals upon the same whereby to regulate the relation of the plate edge and the ink roll, substantially as described.

5. In an ink fountain, the combination of 80 an ink roll, and an ink trough, the bottom of the trough comprising a flexible plate mounted to swing independently of the trough ends upon a pivot eccentric to the ink roll to and from a position with its edge adjacent the roll, and a series of set screws 85 swinging with the plate and arranged to bear at intervals longitudinally upon the margin of the same whereby to regulate the relation of the plate edge and the ink roll, substantially as described.

6. In an ink fountain, the combination of 90 an ink roll, and an ink trough, the bottom of the trough comprising a plate mounted to swing independently of the trough ends to and from a position with its edge adjacent the roll, and a latch member arranged to releasably secure the plate in two fixed positions, one with its edge in operative relation to the roll and the other free of the trough ends to facilitate cleaning, substantially as described.

7. In an ink fountain, the combination of 100 an ink roll, and an ink trough, the bottom of the trough comprising a plate mounted to swing independently of the trough ends to and from a position with its edge adjacent the roll, and a latch member secured to the machine frame and releasably connected to the plate whereby to secure the latter in two fixed positions, one with its edge 110 in operative relation to the roll and the other free of the trough ends to facilitate cleaning, substantially as described.

8. In an ink fountain, the combination of 115 an ink roll, and an ink trough, the bottom of the trough comprising a flexible plate mounted to swing independently of the trough ends to and from a position with its edge adjacent the roll, a series of adjusting members swinging with the plate and arranged to bear at intervals on the margin of the same whereby to regulate the relation of the plate edge and the ink roll, and a slotted latch member arranged to releasably secure the plate in two fixed positions corresponding to the slot end, one with its edge 125 in operative relation to the roll and the other free of the trough ends to facilitate cleaning.

9. In an ink fountain, the combination 130

with the ink trough and its end plates, of a plate forming the bottom of the trough and arranged to swing from a position with its edge adjacent the roll to a position clear of the trough ends, whereby to render the plate and ends accessible for cleaning.

10. In an ink fountain, the combination with the ink trough and its end plates, of a plate forming the bottom of the trough and arranged to swing from a position with its edge adjacent the roll to a position clear of the trough ends, whereby to render the plate

and ends accessible for cleaning, and a series of adjusting screws bearing on the plate edge and mounted to swing with the plate 15 whereby to maintain the adjustment of the plate during cleaning.

In testimony whereof I have hereunto signed my name in the presence of two subscribing witnesses.

EDWARD L. C. CLARK.
